A. PRUTZMANN, OF CANTON, OHIO.

Letters Patent No. 97,809, dated December 14, 1869.

IMPROVEMENT IN MACHINES FOR MAKING FLY-NETS.

The Schedule referred to in these Letters Patent and making part of the same.

To all whom it may concern:

Be it known that I, A. PRUTZMANN, of Canton, in the county of Stark, and State of Ohio, have invented certain new and useful Improvements in Machines for Making Fly-Nets; and I do hereby declare that the following is a full, clear, and exact description of my invention, reference being had to the accompanying drawings, forming a part of this specification, and to the letters of reference marked thereon, of which drawings—

Figure 1 is a plan of my improved machine.

Figures 2 and 2^a are front and side elevations of modified forms of strap-trimmer.

Figure 3 is a front elevation of the strap-burnisher.

Figure 4 is an elevation of the blacking-cup, with cover open.

Figure 5 is a side elevation of my improved machine.

Figures 6 are side, front, and rear elevations of my device for pointing the straps.

Figure 7 is a detail plan of the drawing-cylinder vise.

Figures 8 are plan and elevation of the presser-plate door.

Figure 9 is a front elevation of the knife-pressure roller and yoke.

Figure 10 is a front elevation of the straight-cutting mechanism, detached from the other machinery.

Figure 11 is a cross-section of mechanism shown in fig. 10.

Figures 12 are plan and elevation of the retaining-bar for the pressure-plate door.

Figure 13 is a side elevation of the handle for straight-cutting knife-shaft.

Figures 14 are plan and elevation of the straight-cutting knife-shaft.

Figures 15 are side and end elevations of the device used for cutting out scraps of leather into a circular form, to be cut into small straps.

My invention relates to certain improvements in the construction of machinery for making fly-nets, said improvements consisting in the novel construction of mechanism for cutting scraps of leather which can be rounded into a circular form, into strips suitable for the small straps in fly-nets; also, in the novel construction of mechanism for reducing said small straps to a smooth, round form; also in the novel construction of mechanism for pointing the ends of said straps; also, in the novel construction of mechanism for cutting either the broad or narrow straps used in fly-nets from strips of straight leather; also, in the novel construction of mechanism for punching the different-sized holes in the straps; also, in the novel construction of mechanism for blacking the small straps; these several improvements affording the manufacturer mechanical facilities for performing all the operations required in making fly-nets, thus greatly diminishing the cost and labor of making the same.

To enable others skilled in the art to make and use my invention, I will proceed to describe its construction and operation.

The base of my machine consists of a plate, A, of iron or other suitable material, in the sides of which are cut slots *a a*, in which are bolted various parts of the machine, as hereafter shown.

The face-plate C is secured at one edge of the plate A, and serves, together with a plate at each end, to support the bed-plate B.

The guide-plate T is made with a flange at its front edge, and is secured on the bed-plate B by the screw V, which passes through a raised washer on the plate T, down through a hole in said plate, and through a slot in the plate B, into a bevelled nut under the plate B, which bevelled nut fits in the slot in the plate B, which is also bevelled, thus preventing the nut from turning.

In the plate T is fixed the standard 2, the upper end of which is formed with an eye, through which passes a tension-bolt, with a thumb-nut, Z.

The arm U is pivoted, by a bolt, 1, to the lower end of the standard 2, and the spiral spring 3 connects the end of the arm U with the tension-bolt on which is the thumb-nut Z.

The front end of the arm U extends through a slot in the flange of the plate T, and the roller u is pivoted on it, as shown in figs. 1 and 5.

The arm W has a slot cut in its rear end, through which passes the screw w', by which it is secured to the plate T; and the front end of this arm extends through a slot in the flange of the plate T, and is provided with a thumb-screw, w.

The arm S is also secured to the plate T, on the other side of the arm U, by a screw, t, passing through a slot in its rear end, and extends through a slot in the flange of the plate T, and is provided with a thumb-screw, v, and has a shoulder formed on its under side, a little distance back of the screw v.

The slide-rails Z pass through holes in the plate C, and are fastened by a clamp on the under side of the plate B.

The slide h encircles the rails Z, and on it is pivoted the arm i, the front end of which is provided with the centre-pin k, and the rear end of which is flattened out and bent down against the rail Z, against which it is pressed by the spring j, which is fastened in the slide h, and has its other end pressing against the other rail Z, as shown in fig. 1.

The knife x (see fig. 1) extends up through a slot in the plate B, and is held against a block on the under side of said plate by a bolt, y, which screws through a nut on the under side of the plate B.

The knife x can be made in an ordinary knife-form, or, if preferred, a peculiarly-formed cutter, similar in construction to the trimming-cutter hereinafter de-

scribed, can be used, by which the leather could be partially trimmed to a round section as it was cut off.

The strap-trimmer M7 is composed of the standard M, which is secured by a bolt in a slot, a, in the plate A, and has the cross-bar 11 at its head, to which the upper end of the guide-bar 66 is secured, the lower end of said guide-bar being secured to the standard M, as shown in figs. 2.

The trimming-cutter 7 is made with one or more holes, 88, to suit different sizes of straps, and is of the cross-section shown in detached view in figs. 2, the V-shaped end being ground sharp around the holes 88, and forming around said holes a cutting-edge, which trims the corners from the square strap as it comes to the cutter through a slot in the guide-bar 66.

The lower end of the cutter 7 is made pointed, and fits in a hole in the standard M, and its upper end is formed into a bolt, on which is the jam-nut 9, so that by putting the bolt-end of the cutter 7 into the slot 10, in the cross-bar 11, and turning up the nut 9, the cutter is firmly fixed in the standard.

Two or more standards, M, with trimming-cutters 7, could be used in succession on the plate A, if found desirable, each taking off a portion of the corners of the strap, and thus gradually reducing it to a round section.

The burnisher 12 is fixed in the standard L, on the plate A, and has formed in it one or more holes, 13, of sizes corresponding to the required size of strap.

It is fastened in the standard L by means of one pointed end fitting in a hole in one arm of said standard, while the other threaded end fits in a slot, 15, in the other arm, (see fig. 1,) and is held by a jam-nut, 14, as shown.

In order to insure the strap being drawn correctly through the holes 13, in the burnisher 12, or through the holes 8 of the trimming-cutter 7, in case the burnisher 12 be not used, the standard K is attached to the plate A, and has the grooved wheel 16 journaled in a slot at its upper end, in such a position as that its lower face shall be in line with a hole, 13 or 8, through which the strap is to pass, or in line with each of said holes, which are in line with each other, when both burnisher and trimming-cutter are used.

The vise-drawing-cylinder standard J is bolted to the plate A, and has a head through which passes the shaft 20, having a crank, 1919, at one or both ends, as found desirable.

The vise-cylinder I consists of the jaw I', of a cylindrical form, and of somewhat less circular length than the semi-circumference of the cylinder, and having a circular head at one end, which is fixed to the shaft 20.

The other jaw, 17, is of the same form, but its head is loose on the shaft 20, and is provided with a screw, 18, which works in a nut in said head, and has the cone-shaped wedge 22 at its lower end.

The incline 23 is secured on the jaw 17, and the incline 24 on the jaw I', from which it is readily seen, that by advancing the wedge 22, by means of screw 18, the sides of the jaws I', 17, shown in fig. 7, will be caused to separate and that the other edges of said jaws will consequently approach each other, and grasp the ends of the straps, introduced between them, like a vise, and that when so grasped, the strap can be drawn out and wound on the cylinder I, by turning the cranks 19 or their equivalents.

The lip 21, on the jaw I, works in a slot in the head of the jaw 17, and thus prevents the jaws from separating further than would be desirable, as shown in fig. 5.

The cutter-box N (see figs. 6) is of the general form shown, and has an arm, 65, at one side, by which it is secured by a bolt, 64, to one of the upright pieces under the bed-plate B, as shown in fig. 1.

The cutter-base 32 is secured near the centre of the box N, and on it are secured one or more cutters, 55, by means of the clamp 34 and screw 4.

The cutters 5 are made with grooves in their lower faces, and have their front ends sharpened, so as to present the appearance shown in plan and side elevation in figs. 1 and 6.

The cells 33 are arranged in the box N, under the cutters 5, and the corrugated rod 6, of a square section, is slid into these cells 33, together with the end of the strap to be pointed, which rests on the rod 6, when, by turning the rod 6 upward until the strap is brought between the cutter 5 and rod 6, and then drawing the strap and rod back, keeping the rod 6 pressed against the cutter 5, as shown in fig. 6, it is evident that the strap will be properly pointed.

The frame-piece Y is secured at one end by a bolt to the back plate, under the bed-plate B, and its other end is attached to the double plate 40, which is attached to the ends of the inclined plates 54, 54, (see fig. 11,) which are fastened to the plate C.

A guide-bar, n, is fastened, by a bolt, in a slot in the frame-piece Y, so that by loosening the bolt, it may be moved along said piece to any desired point.

The bolts q q project through holes in the piece Y, and are held by jam-nuts p p, as shown in fig. 1.

The heads r' are fastened on the ends of the bolt q, and in these heads are fastened the tension-rods r r, the other ends of which slide through holes in the compound revolving nuts l m, which are secured in the plate C, as shown in fig. 1.

The straight-cutting knife-shaft 60 is of the form shown in fig. 14, and has a central slot, in which are arranged the knives 61 61, which are maintained at the proper distances apart by the blocks 62 62, which are headed at the ends, as shown in detached view, to prevent any danger of their working up or down in the slot in the shaft 60.

The end block 63 is made longer than the others, so as to act as a gauge to the leather, and the several blocks and knives are firmly secured in the shaft 60, by the clamping-screw 37, as shown.

The shaft 60 is supported between the plates C and 40 by the journals 67 67, one of which fits in a box in the plate C, and the other projects through a box in the plate 40, and has the handle 36 secured by a set-screw, 45, on its end.

The knife-pressure roller-shaft 56 is arranged in slots in the plates C and 40, and has the yoke 57, which slides in said slots, with its ends resting on the ends of the shaft 56.

On this shaft are arranged the rollers 59 59, which are of a width equal to that of the strap to be cut, and which have a collar on one end to keep them a little apart, so as to let the knives 61 61 set up between them, when found desirable, or, if preferred, these rollers 59 can be cut out of leather, and be allowed to set up against each other, in which case, the knives 61 would cut into instead of between them.

The end roller 58 is made larger than the others, so as to act as a gauge to the leather while being drawn through.

The presser-bar door X is of the form shown in figs. 8, and has the journals 46 46, and the back-piece 48, in which are arranged the set-screws 50 50, which press against the plate 49, and thus hold the presser-bar 47 in position.

This bar 47 is of wood, lead, or any soft metal, and is so arranged as that the knives 61 just cut its lower edge when turned up, as shown in fig. 11.

The door X is held, by its journals 46 46, in the plates C and 40, and is held down, either by slotting the holes 41, in the plates 40 and C, in which the journals 46 work, and having the hooks 53 to hook into slots 55 (see fig. 1) in the plates C and 40, by pushing the door X forward when turned down, or by having a retaining-bar, 43, arranged in slots 42, in the plates C and 40, to slide under the rear flange 51 of the door.

The screws 35 35, in the door X, press on the yoke 57, which presses down the knife-rollers 59 59; and the handle 36, of the knife-shaft 60, has a slot, 44, cut in it, in which the adjustable piece 38 may be introduced, by loosening the screw 39 which binds it to the plate 40, when, by adjusting the piece 38 and tightening the screw 39, the movement of the handle 36 and shaft 60 may be limited as desired, in order to prevent the knives 61 from cutting too deeply into or between the rollers 59.

The punch-standard o is bolted to the bed-plate B, and has the lever Q pivoted to it by a bolt, e. (See figs. 1 and 5.)

The punch-slide P is attached, by a bolt, d, which passes through a vertical slot in the standard o, to the lever Q, and a guide-bolt, g, is also fixed in the slide P, and extends through the slot in the standard o and serves to steady the movement of said slide.

The rod f is fixed in the slide P, and extends up through a flange on the side of the standard o, where it is provided with a thumb and clamp-nut, f'.

The slot c is cut in the horizontal arm of the slide P, and in it are secured one or more punches, b, provided with thread and nut at their upper ends, and made of a tapering form, with a cutting-edge, as shown in fig. 5.

A slot is made in the plate B, through which the punches b pass in punching the holes in the leather, and, if desired, a plate of leather or soft metal can be laid on the plate B, under the punches b, for them to punch through, in order to prevent the strap from forcing down in the slot in the plate B.

The gauge R is held by the clamp and screw S on the plate B, and serves as a guide in punching the holes in the strap.

The blacking-cup G H consists of the cup H, which is bolted on the plate A, and has the cover G hinged to it, as shown.

The edge of the cover G is bent up so as to form an entrance-aperture, 26, and an arm, 31, is fixed in the cover G, and extends down nearly to the bottom of the cup, where it is provided with an eye, with a lining of leather if desired.

A clamp, 29, is fastened to the arm 31 at the cover G, and a screw, 27, passes through the cover G into said clamp, by means of which the wiping-leather 30 is held in position below the exit-aperture 28 in the cover G; said cover G being held down by the screw 25, as shown in figs. 1 and 4.

The reel-standard D is bolted to the plate A, and has a head, in which the reel-shaft F works; one end of said shaft having a crank, and the other end having the reel E attached, as shown in figs. 1 and 5.

Where a small round strap is to be formed from a square strap of weak leather, a long, thin trimming-cutter is required, and for this purpose, the trimmer shown in figs. 2° is used.

This consists of a standard, M', which is bolted in the plate A, in place of the standard shown in fig. 1, and on the face of which is secured the retaining-plate 71, as shown.

The cutter 70 is of the tapering form shown, and has a long, thin section, as shown; the hole 80 in said cutter being of the size required for the strap to be trimmed.

The end of this cutter, 70, is made in a conical form, as shown in section at 73, and fits into a corresponding hole in the plate 71, from which it is readily seen, that as long as the retaining-plate 71 is kept drawn up in front of the face of the standard M' by the bolt 72, the cutter 70 will be firmly held in position, but that by loosening the bolt 72, the plate 71 may be turned around said bolt as an axis, away from the standard M', when the cutter 70 may be removed and replaced by another cutter, with a different size of hole, 80, if desired.

Where scraps of leather are to be cut into small straps, by means of the knife x and its attendant mechanism, it is desirable that such scraps should first be cut into a circular form, and for this purpose the device shown in figs. 15 is used.

This consists of the block 81, in the centre of which is the slot 83, and through the end of which passes the clamping-screw 82, as shown.

The guide-wheel 84 is pivoted by a screw at the other end of the block 81, and the knife 85, which is made with a tapering point, is secured in the slot 83, by means of the screw 82, which bears against a block, 86, which rests on the knife, as shown.

In using this device, one leg of a common pair of compasses is secured between the knife 85 and plate 86, and the knife is set so as to project below the wheel 84, (which runs on the leather,) a distance equal to the thickness of the leather.

The other leg of the compasses is then set in the centre of the scrap, and the other leg is so adjusted as to bring the knife 85 into the circumference of the circle to which the scrap is to be reduced, when, by pressing down on the block 81 and turning the compasses, the scrap will be cut out, as desired.

Having thus fully described the construction of my improved machine, its operation will be easily understood from the following description:

When a scrap of leather is to be cut into straps, it is first trimmed into a circular form, by means of a pair of compasses and the device shown in figs. 15, or in any other suitable manner, and a narrow starting-piece is cut from around the edge of the scrap, in its circular form.

The centre of the scrap is then placed over the centre-pin k, and the plate T is then set (by loosening the screw V) so as to bring its flange at the proper distance from the knife x, to cut the required width of strap.

The starting-piece is then passed between the plate T and knife x, under the roller u, thence through a hole, 8, in the trimmer 7, and a hole, 13, in the burnisher 12, under the grooved wheel 16, to the vise-cylinder 1, into which it is clamped, when, by turning the cranks 19, the leather is cut from piece on the centre-pin k, by the knife x, (said pin moving back and forth by the movement of the slide h, on the rails Z, and sidewise by the movement of the arm i around its pivot on said slide, to conform to the movements of the piece of leather from which the strap is being cut, and the arms W and S, with their pressure-screws w and r, aiding the roller u in holding the leather down smooth when found necessary,) and is trimmed into a round form by the cutter 7, and is further reduced and pressed by the burnisher 12, and, finally, is wound up on the cylinder I.

As the last of the strap is cut, and after it has all passed through the burnisher 12—or cutter 7, if no burnisher is used—the end is taken to the box N, and is pointed, after which it is passed through the eye in the arm 31, in the blacking-cup cover G, and through the hole in the wiping-leather 30, and out of the hole 28, and is attached to the reel E, when, by filling the cup H with blacking, fastening down the cover G, by the bolt 25, and turning the crank F, the strap is unwound from the cylinder I, blacked, and wound on to the reel E, as is readily seen.

To cut the straps of leather from a long strip of leather, the guide n is first fixed on the piece Y, at a distance from the plate C equal to the width of the strip to be cut.

The heads r' are then set at the same distance from the plate C, by turning the jam-nuts p; the knives 61 are adjusted at the required distances for cutting the desired width of strap, by the introduction of suitable blocks, 62, (the distance between the guide-block 63 and plate C being the same as that between said plate

and the heads r' and guide n ,) and the rollers 59 and guide-roller 58 are arranged to correspond with the knives 61 and block 63.

The strip to be cut is then introduced into the slot in the piece Y, between the plate O and guide n, and passes over one tension-rod, r, under the next, over the next, said rods being turned so as to give such an amount of tension on the leather as will serve to keep it drawn straight and smooth.

The handle 36 being turned up, as shown in fig. 5, throws the points of the knives 61 down, so that the strip can be passed in between the presser-bar 47 and rear inclined plate 54, and between the front plate 54 and the rollers 59.

The screws 35 are then turned down, so as to bind the rollers 59 down on to the strip of leather, a cord is put through holes in the end of the strip, and its ends are clamped in the vise-cylinder I, which is slid out in front of the cutting-mechanism, when, by turning up the knives 61, by means of the handle 36, into the position shown in fig. 11, they cut through the strip, which is then drawn forward, by turning the cranks 19, and is cut into straps of the required width, as is readily seen, the bar or plate 47 and rollers 59 keeping the leather pressed down on to the knives 61, so as to insure its being cut.

The straps of leather thus cut out together, and wound on the cylinder I, may be separated from each other, and be rounded, pointed, blacked, and wound on the reel E, by the use of the devices hereinbefore described.

The punches b are set in the groove or slot c , in the slide P, at such distances as will cause the holes to be punched at the proper distances from the edge of the strap and from each other, said strap being moved along under the punches, and against the punch-standard o; and the sizes of the holes punched are regulated by turning the nut f' up or down on the rod f, which limits the movement of the conical-shaped punches, and, consequently, the sizes of the holes punched, as is readily seen.

Having thus fully described my invention,

What I claim therein as new, and desire to secure by Letters Patent, is—

1. The guide-plate T, provided with the arm U, with pressure-roller u, and the tension-device 2 z 3, and combined with the bed-plate by the clamping-screw V, substantially as and for the purpose specified.

2. The adjustable arms W S, secured to the plate T by screws w' t, and having the pressure-screws w v at their ends, substantially as and for the purpose specified.

3. The centre-pin k, arranged on an arm, i, pivoted on the slide h, and held by a spring, j, attached to the slide h, and acting between the end of the arm i and the slide-rail Z, substantially as and for the purpose specified.

4. The combination of the plate B with clamping-bolt y and knife x, guide-plate T, with clamping-screw V, and pressure-roller u, arranged on arm U, with tension-device 2 z 3, and slide-rails Z with slide h, having arm i, with centre-pin k and spring j attached thereto, the several parts being arranged substantially as and for the purpose specified.

5. The trimming-cutter 7, provided with the jam-nut 9, when used in combination with the standard M 11, provided with the slot 10, substantially as and for the purpose specified.

6. The trimming-cutter 70, provided with the conical end 73, when used in combination with the retaining-plate 71, with clamping-bolt 72, and the standard M, substantially as and for the purpose specified.

7. The burnisher 12, provided with one or more

holes, 13, and secured by the jam-nut 14, in the standard L, with slot 15, when used in combination with the trimming-cutter 7 or 70, substantially as and for the purpose specified.

8. The standard K, with grooved wheel 16, when used in combination with the burnisher 12 or trimming-cutter 7 or 70, substantially as and for the purpose specified.

9. The vise-cylinder I, composed of the jaw I', fixed to the shaft 20, and provided with the incline 24 and lip 21, and the jaw 17, provided with screw 18 and wedge 22 and incline 23, the several parts being combined and arranged substantially as and for the purpose specified.

10. The cutter-box N, provided with clamp-screw 4, clamping-piece 34, cutter-base 32, and one or more cutters, 5, with corresponding cells, 33, the several parts being arranged substantially as and for the purpose herein specified.

11. The corrugated slide-rod 6, when used in combination with the cutter-box N, provided with cutters 5 and cells 33, substantially as and for the purpose specified.

12. The tension-rods r r', fixed in the head r', and sliding through the compound revolving nut l m, in the plate C, and held in position by the jam-nuts p p, on the rod q, in the head r', in combination with the frame-piece Y, substantially as and for the purpose specified.

13. The straight cutting-knife shaft 60, provided with clamping-bolt 37, journals 67 67, and handle 36, and having the knives 61 61 secured between the headed blocks 62 62 63, substantially as and for the purpose specified.

14. The adjustable stop-piece 38, secured to plate 40 by screw 39, when used in combination with the handle 36, provided with slot 44, on the knife-shaft 60, substantially as and for the purpose specified.

15. The pressure-bar door X, arranged to turn on journals 46 46, working in holes 41 41, in the plates C and 40, and provided with pressure-screws 35 35, and pressure-plate 47, held by clamp 49 and screws 50 50, and held in position either by hooks 35 35, or the retaining-bar 43, substantially as and for the purpose specified.

16. The shaft 56, provided with rollers 58 59 59 and yoke 57, and held down by pressure-screws 35, when used in combination with the knives 61 61 and the front plate 54, substantially as and for the purpose specified.

17. The punch-arm P, provided with the slot c, with one or more punches, b b, of a conical form, secured therein, and the adjusting-rod f, with nut f', when used in combination with the punch-standard o, hand-lever Q, and plate B, substantially as and for the purpose specified.

18. The blacking-cup G H, composed of the cup H, with cover-screw 25, and the hinged cover G, with entrance and exit-apertures 26 28, dipping-arm 31, and wiping-leather 30, held by clamp 29 and screw 27, the several parts being arranged substantially as and for the purpose specified.

19. The reel E, mounted on standard D, on the frame A, and provided with crank F, when used in combination with the blacking-cup G H, also secured on the plate A, substantially as and for the purpose herein specified.

As evidence that I claim the foregoing, I have hereunto set my hand, in the presence of two witnesses, this 25th day of September, A. D. 1869.

A. PRUTZMANN.

Witnesses:

JOB ABBOTT,
D. HAMMOND.
